(57) **CLAIM**

The ornamental design for a display screen with graphical user interface, as shown and described.

DESCRIPTION

FIG. 1 is a front view of a display screen with graphical user interface shown on a monitor.

FIG. 2 is a front view of the display screen with graphical user interface shown on the monitor, with the design shown in another environment.

FIG. 3 is a rear view of the monitor.

FIG. 4 is a top view of the monitor.

FIG. 5 is a bottom view of the monitor.

FIG. 6 is a right side view of the monitor.

FIG. 7 is a left side view of the monitor.

FIG. 8 is a front view of the display screen with graphical user interface on a second monitor.

FIG. 9 is a front view of the display screen with graphical user interface shown on the second monitor, with the design shown in another environment.

FIG. 10 is a rear view of the second monitor.

FIG. 11 is a top view of the second monitor.

FIG. 12 is a bottom view of the second monitor.

FIG. 13 is a right side view of the second monitor.

FIG. 14 is a left side view of the second monitor; and,

FIG. 15 is a perspective view of the display screen with graphical user interface shown on the second monitor in a use environment.

The broken lines in the drawings illustrate portions of the display screen with graphical user interface and environmental subject matter that form no part of the claimed design.
